(57) **CLAIM**

I claim the ornamental design for a hand held underwater propulsion device, as shown and described.

DESCRIPTION

FIG. 1 is a perspective view showing the front in perspective. FIG. 2 is a perspective view showing the rear in perspective. FIG. 3 is a perspective view showing the rear and top view in perspective.

FIG. 4 is a side view.

FIG. 5 is a rear view.

FIG. 6 is a bottom view; and,

FIG. 7 is a top view.

The broken lines are for environmental purposes and form no part of the claimed invention.
